Inventor
John M. Hancock

UNITED STATES PATENT OFFICE.

JOHN M. HANCOCK, OF LANSING, IOWA.

FIRE-ESCAPE.

Specification of Letters Patent No. 23,462, dated April 5, 1859.

To all whom it may concern:

Be it known that I, JOHN M. HANCOCK, of Lansing, in the county of Allamakee, State of Iowa, have invented a new and useful 5 Improvement in Fire-Escapes; and I do hereby declare that the following is a full, clear, and exact description of the construction and operation of the same, reference being had to the annexed drawings, being a 10 part of this specification, in which—

Figure 1, is a perspective view of my improvement attached to a table when not in use. Fig. 2, represents my improvement ready for use but the works not in motion. 15 Fig. 3 is a transverse view with the works in motion.

This invention consists in providing works similar to those of a clock consisting of roller, a ratchet wheel "B," and pawl 20 "N," with driving wheels "C" and "D," the driving wheel, "D" acting in the pinions of the fly wheels "E," "E." Attached to the driving wheel "D," is a rim "P," near the outer edge, also a number of pins 25 "g," are attached to the spokes of said wheel, which when the wheel is in motion strike on the spring "M," which serves as a brake. There is also a block brake "y" with a cord "w" attached, which acts on 30 the rim of the driving wheel "D," the rope which is attached to the brake "y," is to be used by the person descending in the basket "W," or its equivalent, which basket is attached by a rope "H," to the roller "A," 35 acting the same as the weight of a clock. The whole weight is detained from descending by the detent or stop "x," which stop acts on one of the fly wheels "E." When a person is ready to descend turn the crank 40 "O," one fourth round, which will free the fly wheel "E," from the detent "x" and permit you to safely descend to the ground. The whole of the works are made fast in the draw, or attached to the top of a table "S," 45 or its equivalent which is attached by means of two hooks and chained to the window sill. There is also attached to the basket "W" or its equivalent a cord "u" which can be used to assist the person descending to guide the 50 basket so as to enable them to avoid fire which may be issuing from the windows beneath.

The operation of the apparatus is as follows. On the occasion of a fire the table 55 "S" or its equivalent is put out of the window the top of the table resting against the

wall of the building, the basket will then hang down by its own weight and is prevented from descending by the detent "x" until the person wishing to descend in 60 safety, is in the basket, then turn the crank "O" one fourth of a revolution. This crank is near to the hand of the person who may be in the basket, the fly wheel will be let loose, and the person will descend in safety, 65 the weight of the body being retarded in its descent by the spring brake "M" the retarding power being regulated to one hundred and forty pounds. When much heavier weight is attached to the basket 70 "W" or its equivalent, the person descending can pull on the cord "w" attached to the brake "y" with which they can retard their descent to suit themselves. If fire should be issuing from windows beneath the 75 cord or its equivalent "u," attached to the basket "w" will enable a person beneath to guide it on one side. The basket is then wound up by the next waiting to descend by the crank "K" which is under the top of the 80 table and near to the wall, when by turning the crank "O" back the basket is detained until the person is ready to descend.

I do not intend to confine myself to the precise mode of winding up the machine as 85 it may be varied and in fact must be when the form of the case or piece of furniture in which it is inclosed is changed. Nor do I confine myself to the materials of which the basket is composed, as in changing the case 90 the materials of the basket must be changed also.

I am aware that the use of the flying pinion as a retarding power is not new, therefore separately considered I do not claim 95 them, but

I do claim and desire to secure by Letters Patent:

1. The flying pinions "E," "E" in combination with the detent "x" the driving wheel "D" the spring brake "M" and block brake "y" as substantially described and for the purpose set forth.

2. I also claim in combination with the described piece of mechanism the table or 105 its equivalent as substantially described and for the purpose set forth.

JOHN M. HANCOCK.
